UNITED STATES PATENT OFFICE.

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LOOM TO TRANSFER ON BACKWARD STROKE OF THE LAY.

Application filed October 28, 1925. Serial No. 65,438.

This invention relates to improvements in automatic weft replenishing looms and it is the general object of the invention to provide means for transferring weft into any one of a plurality of shuttles on the backward stroke of the lay without stopping any normally moving part of the loom.

In certain types of looms which employ a plurality of boxes on each end of the lay 10 to accommodate a plurality of shuttles the movement of the boxes to bring successive shuttles into active position takes place while the lay is forward and it is a difficult matter to transfer a bobbin into a shuttle 15 when the lay is in this position. In such looms, however, there is always at least one idle shuttle which is at rest with respect to the lay when the latter is in its rear position and I propose to make use of this fact by 20 providing mechanism which will introduce a fresh supply of weft into an idle shuttle when the lay is in backward position.

In so-called pick and pick looms where it is necessary to lay single picks it is found 25 that the boxes at each end of the loom are likely to move every pick and my invention relates more particularly to this style of loom.

It is a further object of my invention to 30 provide a weft replenishing mechanism at each side of the loom, one to supply one color of weft and the other to supply another color of weft, the specific embodiment of my invention set forth herein being a two 35 color loom wherein the shuttles change their position each pick of the loom.

It is a further object of my invention to 40 provide weft detectors in relatively fixed positions which will cooperate with the shuttles on the backward stroke of the lay, so that neither the replenishing nor the detecting is accomplished on the front center of the lay as is usual with looms having a single box on at least one side of the lay.

It is a still further object of my invention 45 to provide a transfferer receiving a regular motion on every fourth pick to cooperate with the detecting mechanism so that when the latter indicates a bobbin will move under

50 the transfferer and be inserted in the in-

dicating shuttle the next time it is in proper position for transfer.

It is a still further object of my invention to accomplish the transfer of the weft, and also the detecting, while the boxes are in 55 one or another of their normal positions, no abnormal motion of the boxes being required to accomplish replenishment.

With these and other objects in view which will appear as the description 60 proceeds, my invention resides in the combination and arrangement of parts herein-after described and set forth in the claims.

In the accompanying drawings, wherein the invention is illustrated in connection 65 with a two-shuttle loom having two boxes at each end thereof which receive regular movements on every pick of the loom,

Fig. 1 is a side elevation of a loom having my invention applied thereto showing 70 a portion of the lay in section,

Fig. 2 is a front elevation of the loom shown in Fig. 1,

Fig. 3 is an enlarged rear elevation of the upper part of one end of the loom showing 75 the relation of one of the weft replenishing mechanisms and the detector connections for the other weft replenishing mechanism.

Fig. 4 is an enlarged top plan looking in the direction of arrow 4, Fig. 1, 80

Fig. 5 is an enlarged side elevation of one of the weft replenishing mechanisms.

Fig. 6 is a vertical section on an enlarged scale on line 6—6 of Fig. 5,

Fig. 7 is an enlarged view of the detector 85 and lay showing the latter on back center and the boxes in down position,

Fig. 8 is an enlarged section on line 8—8 of Fig. 1,

Fig. 9 is a detail vertical section on line 90 9—9 of Fig. 5,

Figs. 10, 11, 12 and 13 are diagrammatic views indicating the relative positions of the boxes and shuttles for four successive picks when the lay is on back center, 95

Fig. 14 is a vertical transverse section on line 14—14 of Fig. 4, and

Fig. 15 is a vertical longitudinal section on line 15—15 of Fig. 4.

The loom set forth herein is provided with 100

duplicate weft changing mechanisms on each side thereof, each mechanism having a weft detector, a magazine actuating device, a one-color magazine which is under the joint control of the detector and actuating device, and a regularly moving transference arm. The detector of each mechanism is on one side of the loom and the other devices are on the opposite side. Each end of the lay is provided with a pair of separated boxes so controlled that when the boxes at one side are down the boxes at the opposite side are up, the boxes receiving a motion every pick. When the boxes are up the upper box is operatively positioned with respect to the associated magazine and when the boxes are down the lower box is in operative position with respect to the corresponding weft detector. The box controlling and weft changing mechanisms are identical except for the settings of the operating cams and a description of one will suffice for both.

Box motion.

Referring to the drawings it will be seen that I have provided a loom 20 having a lay 21 supported on lay swords 22 and rocked back and forth by means of connectors 23. Each end of the lay is provided with box guides 24 which receive vertically moving boxes 25. By referring to Figs. 1, 2, and 7 it will be seen that each end of the lay is provided with two boxes, the upper box 26 being spaced from the lower box 27 so as to afford an opening 28 through which an expelled bobbin may pass.

Each set of boxes is mounted on a box rod 29 operatively connected to a box lever 30 pivoted as at 31 to a fixed part of the loom 40 and having at the rear end thereof a roll 32 which is in contact with cam 33 secured to the bottom shaft 34. The shaft 34 makes one revolution every two picks and each cam 33 has a low dwell 35 and a high dwell 36, the dwells being connected by inclined surfaces 37 by means of which the lever 30 is moved from one to the other of its positions. The cams 33 are set oppositely to each other so that when the boxes on one end of the lay are going up those on the other end are going down, the movement of the boxes occurring when the lay is approximately in the forward half of its stroke.

By referring to Figs. 10 to 13 the positions the boxes assume on successive picks with the lay in rear position will be understood. As seen in Fig. 10 the left hand boxes are down and a shuttle S^r is traveling from the upper of said boxes toward the lower right hand box, the right hand boxes being up and the upper right hand box being occupied by a shuttle S^g . As the lay moves forward the boxes will change to the position shown in Fig. 11, shuttle S^g moving to the left and shuttle S^r being in lower position. On the

next beat of the loom the boxes return to their starting positions (see Fig. 12) but shuttle S^r is now moving to the left and shuttle S^g is in lower position on the left hand side. On the fourth beat the boxes again change as seen in Fig. 13, shuttle S^g moving to the right and shuttle S^r being in upper position. This is the end of the repeat and the next movement of the boxes returns them to the position shown in Fig. 10 and the sequence will be repeated. It will be noted that shuttle S^r is in an upper box on the left side only and that shuttle S^g is in an upper box on the right side only. Furthermore, it will be seen that when each shuttle is in a lower box it is on that side of the loom opposite to the side where it occupies an upper box. Also, it takes four picks for each shuttle to return to any given position.

The weft changing mechanisms to be described hereinafter depend for their proper operation upon the sequence of shuttles just described, the detecting mechanisms cooperating with the shuttles when they are up. I will now describe one of the detecting mechanisms, namely, the one located at the left hand side of the loom.

Weft detecting mechanism.

Referring to Figs. 1, 4, 7, and 14 it will be seen that I have secured a stand 40 to the frame 20 and have secured therein for vertical adjustment a post 41 the upper end of which is threaded into the base 42 of the detector D. Said base 42 has a slightly inclined guide 43 having a slot 44 therein to receive a detector slide 45. As shown in Fig. 4 the slide has pivoted thereto as at 46 a laterally swinging feeler jaw 47 having a roughened yarn engaging surface and has secured thereto a yarn penetrating wedge 48 the small end of which projects slightly beyond the jaw 47.

The feeler jaw has extending laterally therefrom an arm 49, (see Fig. 4) the forward face of which is engaged by a hooked rod 50 located in the slide 45 and extending rearwardly to receive a stop screw 51. Said screw 51 normally engages the guide 43 and serves to hold the jaw 47 against the wedge 48 when the slide is held forwardly in its usual position. A second rod 52 extends through the slide and is pressed against the rear face of arm 49 by a lever 53 secured to rod 54 rotatable in fixed structure. Tension spring 55 is interposed between a fixed point and an extension on lever 53 and serves to hold the said lever against rod 52. In order that spring 55 may not move jaw 47 away from wedge 48 under normal conditions, I secure to the upper face of slide 45 a clip 56, (see Fig. 15) and pass therethrough a pin 57 adjustably mounted in cap 58 held to the guide 43. A compression spring 59

around pin 57 engages clip 56 and holds the slide 45 yielding in forward position, maintaining engagement between screw 51 and guide 43 to hold the jaw and wedge as shown in Fig. 4.

When sufficient yarn is present the slide and feeler jaw move rearwardly without relative movement and push lever 53 rearwardly to give rod 54 a counterclockwise motion as viewed in Fig. 7. When insufficient yarn is present to resist lateral movement of jaw 47, wedge 48 will engage the bobbin B and move the slide rearwardly, but as the jaw is free, it will move to the side under action of rod 52 and the lever 53 will remain at rest. The detector is substantially the same in construction and operation as that shown in Patent No. 1,352,536. I will now describe the magazine actuating device at the opposite side of the loom.

Magazine actuating mechanism.

When the rod 54 is not oscillated on a detecting beat it is necessary to initiate replenishment, this being accomplished through the intermediary of the actuating mechanism A, (see Figs. 3, 5, and 6). As seen in Fig. 3 rod 54 has secured thereto an upstanding finger 70 the upper end of which is connected to a controller pin 71 extending forwardly through a stand 72 held in fixed position. An actuator lever 73 has the left end freely movable in the stand but normally held above the controller pin. Said lever 73 is floated intermediate its ends on a rod 74 connected at its lower end to one end of a cam lever 75 movable about a fixed center and having the other end in engagement with a cam 76 secured to a stub shaft 77 passing through a fixed bearing 78. Secured to the other end of shaft 77 is a gear 79 which meshes with a second gear 80 having half as many teeth as gear 79 and secured to the bottom shaft 34. As the bottom shaft rotates once in two picks it will be seen that cam 76 receives a complete revolution once in four picks.

The cam 76 has a single projection 81 to give the floating or actuating lever 73 a downward motion every fourth pick when the shuttle corresponding thereto is in lower position and on the opposite side of the loom cooperating with its detector. The detector may therefore enter an empty box or it may remain below the boxes when they are raised without giving a false indication due to the four pick motion of the actuating lever.

If rod 54 is rocked on a detecting beat the controller pin will be withdrawn and lever 73 will descend without interruption, but should said rod remain at rest due to a depleted shuttle the controller pin will remain under the actuator lever and as the latter descends the left end as seen in Fig. 3 will remain up and the right end will be depressed to lower an actuating connector

rod attached to lever 73. The actuating mechanism is similar to that shown in Patent No. 1,030,748, and it will be understood that the down motion of rod 82 sets the magazine for replenishment on the second subsequent 70 pick. I will now proceed to a description of the magazine.

Weft magazine.

I employ two single color weft replenishing magazines, one on one side of the loom for one color and the other on the opposite side for a different color. The right and left hand magazines will be designated M^r and M^l, respectively, and a description of 80 magazine M^r will follow.

Referring to Figs. 2, 5, 6, and 9 it will be seen that the magazine comprises inner and outer plates 90 and 91, respectively, between which extend the bobbins B to be transferred. The bobbins are arranged in a single vertical stack by means of guide flanges 92, (see Figs. 5 and 9) and are held in place by a slide cradle 93 formed of two parts 94 and 95 which are movable relatively to each other. Each part has an upper shelf 96 and a lower shelf 97, shelves 96 being normally in outer position and shelves 97 being in inner position to retain and support the bobbins. The parts have diagonal oppositely extending slots 98 through which extends pin 99 carried at the bottom of a vertical slide 100 guided in boxes 101 on the frame 90. The lower end of the vertical slide is forked to receive the cradle parts 94 and 95 and as the slide is raised the parts undergo opposite movements to cause the upper shelves to move inwardly under the next to the bottom bobbin and to cause the lower shelves to move away from each other to release the bobbin normally in the cradle. 100

The movement of the slide is accomplished by a rock shaft 102 rotatably mounted on the plate 90 and having an arm 103 secured thereto and connected to the connector rod 82. As the latter is depressed at indication of weft exhaustion shaft 102 rocks and causes a finger 104 rigid with the rock shaft to raise slide 100 by lifting lug 105 thereon. After projection 81 passes the lever 75 spring 106, which is connected to slide 100 and a boss 101, will pull the slide 100 down and restore shaft 102 and rod 82 to normal position. The return of slide 100 will also restore the cradle to normal position and a 115 fresh bobbin will fall therein.

When the lowermost bobbin is released by the cradle it will fall on yielding supports 107 and will remain there until transferred two picks later. Inasmuch as the sequence of the boxes is definite and it is known in advance that the boxes will rise to present the upper one operatively under the magazine two picks after an indication, the transfer mechanism can be operated at regular 125 130

intervals four picks apart and I will now describe how this result is accomplished.

Transfer mechanism.

- 5 Secured to and moving with stub shaft 77 is a cam 110 (see Figs. 1, 2, and 8) having a single projection 111 to cooperate with a transerrer cam lever 112. A connector 113 attached to lever 112 is pivoted at the upper 10 end thereof to a transerrer arm 114 and causes the arm 114 to descend every fourth beat of the loom at a time when the boxes on that side of the loom are in raised position and when they are at the rear end of 15 the to and fro stroke of the lay. As the arm 114 descends it will move the fresh bobbin resting on the yielding supports 107 into the shuttle; the expelled bobbin passing out through the opening 28 between the boxes.

20 *Summary.*

From the foregoing description it will be apparent that I have provided a lay having at each end thereof a plurality of boxes each 25 of which may assume an operative position with respect to the lay and that the transfer of weft will take place into one of the boxes while it is in a normal position, that is, it is not necessary to give the boxes an 30 abnormal motion in order to effect transfer. It is to be understood, as previously stated, that I have provided duplicate weft changing mechanisms, one for each of the shuttles and that both the detecting and the 35 transferring operations are accomplished while the lay is in its backward position and that these operations take place in connection with the shuttles which are idle. I believe I am the first to provide means for 40 transferring into an idle shuttle on the backward stroke of the lay, this being the only point in the cycle of a loom having boxes on both ends where the shuttle is momentarily at rest. The shuttles previously described 45 are of opposite hands, the shuttle which is replenished by magazine M^g having the eye on the right hand end and the other shuttle having the eye on the left hand end.

Having thus described my invention it 50 will be apparent that changes and modifications may be made therein by those skilled in the art without departing from the spirit and scope of the invention, and I do not wish to be limited to the details herein disclosed but what I claim is:

1. In a loom, a lay movable backwardly and forwardly therein, shifting shuttle boxes on the lay movable relatively to the lay when the latter is in its forward position and stationary with respect to the lay when the latter is in its rear position, said boxes accommodating a plurality of shuttles all but one of which are idle when the lay is in backward position, and means to 60 effect replenishment of weft into an idle 65

shuttle while the lay is in its backward position.

2. In a loom, a lay movable backwardly and forwardly and having a plurality of boxes to accommodate a plurality of shuttles, said boxes being movable normally with respect to the lay when the latter is in its forward position and being stationary with respect to the lay when the latter is in its rearward position, and means to effect a 70 change of filling in one of the shuttles in one of the boxes when the lay is in its rear position.

3. In a loom, a lay movable backwardly and forwardly in the loom, shifting shuttle 80 boxes carried by the lay and movable with respect to the lay when the latter is in its forward position and stationary with respect to the lay when the latter is in its rearward position, and means to effect weft replenishment when the boxes and lay are in 85 rearward position.

4. In a loom, a lay movable backwardly and forwardly in the loom, a set of shifting shuttle boxes carried by the lay movable 90 with respect to the lay when the latter is in its forward position and normally stationary with respect to the lay when the latter is in its rear position, said boxes being capable 95 of assuming any one of a plurality of normally stationary positions with respect to the lay when the latter is in its rearward position, and means to effect a change of filling in one of the shifting boxes when the latter assumes one of the normally stationary 100 positions it may have with respect to the lay when the latter is in its rear position.

5. In a loom, a lay movable backwardly and forwardly therein, a set of shifting shuttle boxes on the lay movable with respect to the lay when the latter is in its forward position and at rest with respect to the lay when the latter is in its rearward position, a transerrer mechanism movable in a fixed path, and means cooperating with 105 the transerrer to effect a change of weft when the lay is in its rearward position.

6. In a loom, a lay movable backwardly and forwardly therein and having a plurality of shuttles all of which are movable 115 with respect to the lay when the latter is in its forward position and all of which with the exception of the active shuttle are at rest with respect to the lay when the latter is in rearward position, and means to effect a 120 change of filling in one of the shuttles other than the active shuttle when the lay is in its rearward position.

7. In a loom, a lay movable backwardly and forwardly therein and having a plurality of shuttles all of which are movable 125 with respect to the lay when the latter is in its forward position and at least one of which is idle when the lay is in its rearward position, and means to effect replenishment 130

of an idle shuttle when the lay is in rearward position.

8. In a loom, a lay movable backwardly and forwardly therein, a set of shifting shuttle boxes on the lay movable with respect to the lay when the latter is in forward position and at rest with respect to the lay when the latter is in rearward position, weft replenishing mechanism operatively positioned with respect to one of the boxes on a changing beat of the loom when the lay is in its backward position, and means to effect replenishment when the lay is in its rearward position and the replenishing mechanism is operatively positioned with said one of the boxes.

9. In a loom, a lay having a regular cycle of movement as the loom operates, a set of shifting shuttle boxes and shuttles therefor, the boxes being movable relatively to the lay during a portion of the cycle of the lay, one of the shuttles being in flight during another portion of the cycle of the lay, and

another shuttle being at rest relatively to the lay during said other portion of the cycle when one shuttle is in flight, a magazine to hold a reserve supply of bobbins and means to effect a transfer of a bobbin from the magazine to the shuttle at rest relatively to the lay while the first named shuttle is in flight.

10. In a loom, a lay having a regular cycle of movement every pick of the loom, a magazine having a reserve supply of weft carriers, a plurality of shuttle boxes and shuttles, one of which is in flight during a portion of the cycle of movement of the lay while another shuttle is at rest relatively to the lay when the first shuttle is in flight, and means to move a weft carrier from the magazine into the shuttle box corresponding to the shuttle which is at rest relatively to the lay while the first named shuttle is in flight.

In testimony whereof I have hereunto affixed my signature.

RICHARD GREENLEAF TURNER.
